COLLAPSIBLE TUBE

Joseph B. Roerig, Chicago, Ill.

Application July 21, 1933, Serial No. 681,449

3 Claims. (Cl. 221—60)

This invention relates to collapsible tubes suitable for containing tooth pastes, shaving, and other creams, or medical or other paste compounds.

5 An object of the invention is the provision of a novel and improved collapsible tube.

More specifically, this invention has for an object the provision of a closure member substantially of the same diameter as an expanded collapsible tube to which the closure member may be permanently, as distinguished from removably, fixed and sealed, whereby to avoid the expense of threading the neck of such a collapsible tube and a cap therefor, and whereby to avoid the inconvenience and loss of time resulting from detaching such threaded caps from the threaded neck and replacing the same in the use of the tube.

Another object of the invention is the provision of a unitary collapsible tube and closure assembly which is slightly in appearance, inexpensive to manufacture, and convenient for use.

With these and other objects in view, the invention consists in certain novel features of construction and combination and arrangement of parts which will be hereinafter more fully described and claimed, in connection with the accompanying drawing.

Referring to the drawing:

30 Fig. 1 is an elevational view of a collapsible tube embodying the features of the invention;

Fig. 2 is a plan view partially in section, of a novel closure member for collapsible tubes;

Fig. 3 is a transverse vertical section through the closure member shown in Fig. 2, and illustrates a suitable connection between the closure member and the collapsible tube;

Fig. 4 is a fragmentary elevation, partially in section, of a collapsible tube illustrating a slightly modified form of closure member; and

Fig. 5 is a plan view of the closure member shown in Fig. 4.

In order to accomplish the foregoing objects, the novel and improved collapsible tube of the present invention includes, as illustrated in the drawing, a container 11 of the squeeze-type which has an annular mouth or open end 12 and a closed end 12'. A hollow cylindrical member or cap 13 having a flat portion or crown 14 and depending side walls or a skirt 15 integral with the crown 14, of substantially the same diameter as the container 11 or its mouth or open end 12, is adapted to close the open end 12.

The cap 13 is formed with an enlarged portion or flange 16 marginally of the depending skirt

15 for engaging the mouth or open end 12 of the tube 11 where the cap 13 may be suitably secured to the tube as by soldering or welding for the purpose of providing a seal with the tube 11, and for the purpose of permanently, as distinguished from removably, connecting the cap and the tube to form a unitary assembly.

5 A discharge orifice or slot 17 is cut or otherwise formed in the depending skirt 15 of the cap 13 between the open end 12 of the tube 11 and 10 the crown 14 of the cap. The cap 13 is also provided with an arcuate recess or slot 18 cut or otherwise formed in and concentrically with the crown 14 and subtending preferably an angle of from 30° to 45° for a purpose which will more 15 fully be described presently.

A second cap 19 is rotatably secured as by a rivet 21 coaxially with the tube 11 and the cap 13 on the crown 14, and has a crown 22 and depending side walls or a skirt 23 integral with 20 the crown 22 and outwardly adjacent the crown 14 and the depending skirt 15, respectively.

The second cap 19 may be polygonal (see Figs. 1 to 3, inclusive) or round (see Figs. 4 and 5), so long as the inside of the cap 19 conforms substantially to the configuration of the outside of the cap 13. Preferably, the external shape of the cap 19 is provided hexagonal as shown in Fig. 1, or octagonal as shown in Fig. 2, to facilitate the rotation of the cap by means of the thumb of 30 the hand holding the tube 11 in the use of the novel unitary tube and closure assembly.

For cooperating with the discharge orifice or slot 17 in the cap 13, a slot or orifice 24 is provided in a side wall or the depending skirt 23 of the cap 35 19. This slot or orifice is in such a position that when the cap 19 is rotated or rocked about the rivet 21, the orifice 24 is adapted to register with the discharge orifice 17 for providing a discharge outlet or port for the tube 11. For the purpose 40 of limiting the travel or throw of the cap 19, a pin or lug 25 depends from the crown 22 and engages in the arcuate recess or slot 18 in the crown 14. Preferably this pin or lug is upset to provide an enlarged portion 26 for bearing against 45 the under side of the crown 14 to hold the adjacent crowns 14 and 22 in their proper respective positions. The arrangement of the pin 25 and the slot 18 is such that the cap 19 may be rocked between a position wherein the orifices or slots 17 50 and 24 are in registration and a position wherein the slot or orifice 24 is angularly displaced from the slot or orifice 17. In the latter position the discharge orifice or slot 17 is closed, as shown in Fig. 2.

Thus it will be seen that the invention provides a unitary tube and closure assembly of substantially the same diameter throughout its length, wherein the closure member is permanently, as distinguished from removably, attached to the open end of the tube, and wherein the closure member may be readily and conveniently manipulated by the thumb of the hand holding the unitary assembly without necessitating the removal of a separate member which may be dropped or lost after it is detached from the tube. It will also be seen that the cap 19 and the cap 13 nested therein with the registerable orifices 24 and 17, provide a paste dispensing control valve and that, by virtue of the unitary assembly, the threading operation on the neck of the tube and the threading operation of a separate cap for fitting the threaded neck of the tube, are avoided, with the result of a more convenient, less expensive, and more sightly collapsible tube.

While I have illustrated and described a preferred embodiment of my invention, many modifications may be made without departing from the spirit of the invention, and I do not wish to be limited to the precise details set forth but desire to avail myself of all changes within the scope of the appended claims.

I claim:

1. A paste dispenser comprising a collapsible tubular container of substantially uniform diameter throughout its length and having an open end, a cap having a crown and a skirt portion integral with said crown, said skirt portion having a peripheral flange at its end opposite said crown, said peripheral flange being permanently secured in said open end of said container whereby said cap provides a closure member for the open end of said container, said skirt portion having a paste dispensing aperture therein intermediate said flange and said crown, another cap conforming substantially to the configuration of and rotatably secured to the first said cap and having a crown and a skirt portion integral with said

crown, the last said crown and skirt portion being outwardly adjacent the first said crown and skirt portion respectively, the skirt portion of said other cap being of substantially the same diameter as said container and having an aperture registerable with said paste dispensing aperture, and means for limiting the rotation of said other cap. 5

2. A paste dispenser comprising a collapsible tubular container of substantially uniform diameter throughout its length and having an open end, a cap having a crown and a skirt portion integral with said crown, said skirt portion being permanently secured in said open end of said container whereby said cap provides a closure member for the open end of said container, said skirt portion having a paste dispensing aperture therein, another cap conforming substantially to the configuration of and rotatably secured to the first said cap and having a crown and a skirt portion integral with said crown, the last said crown and skirt portion being outwardly adjacent the first said crown and skirt portion respectively, the skirt portion of said other cap being of substantially the same diameter as said container and 15 having an aperture registerable with said paste dispensing aperture, and means for limiting the rotation of said other cap. 20

3. In a collapsible tube having an open end, a closure assembly therefor comprising a pair of 30 coaxial hollow caps nested one within the other, the inner of said caps having a skirt portion extending outside of the outer of said caps, said skirt portion having a peripheral flange adapted to be secured in said open end, said skirt portion 35 having an outlet port therein, pivot means rotatably securing the outer of said caps coaxially to the inner of said caps, the outer of said caps being provided with a skirt portion bearing on said peripheral flange and having a port registerable with said outlet port, and means for limiting the rotation of the outer cap. 40

JOSEPH B. ROERIG.
